PREFORMED ACOUSTIC UNIT.

Application filed November 30, 1926. Serial No. 151,769.

This invention relates to pre-formed acoustic units, and the assembly and merger of a plurality of units into a unitary acoustic surface.

- 5 Among the objects of the invention are; to provide an acoustic treatment of high efficiency as to sound absorption; to provide an acoustic treatment as a series of pre-formed units; to provide a series of pre-formed units arranged for association on a surface to be acoustically treated; to provide an acoustic treatment in which there is an absence of visible seams; to provide an acoustic treatment in the use of which lath and plaster may be eliminated either in whole or in part; to provide an acoustic treatment applicable to any surface of a building structure; to provide a series of pre-formed acoustic units applicable to a surface by mechanical fastening devices; to provide an acoustic treatment of such formation as to be applied to a desired surface without the use of highly trained operators; to provide an acoustic treatment which acts as a seal against the infiltration of dust; to provide an acoustic treatment effective as a fire barrier as well as a heat insulator; to provide an acoustic treatment having a visual effect as of rough plaster which is compatible with most architectural schemes; and many other objects and advantages as will be more apparent as the description proceeds.

As will more clearly appear hereafter, the acoustic treatment of this invention can be applied to any surface of a building structure, whether finished or unfinished, whether horizontal or vertical, and to any material forming such surface.

The invention in the preferred form comprises a backing layer of material, a layer of felt mounted thereon, and a membrane in intimate engagement with the felt having projecting flaps at desired edges to overlap with the adjacent unit.

In the accompanying drawings, Fig. 1, represents a fragmentary bottom or "reflected" plan of an acoustic treatment according to this invention, in position on a ceiling, Fig. 2, represents a vertical section through a pair of abutting pre-formed units in their attached position relative a surface,

but prior to the final over-lapping engagement of the respective flaps, and Figs. 3 to 8 inclusive are details of the invention. 55

Each unit of a series has a backing or backing layer 11, formed preferably of a semi-rigid composition such as to impart rigidity to the entire unit, but which may yield as occasion demands, such for instance as in its application to a curved surface. The range of materials of which the backing may be formed is rather wide and the particular layer used should be chosen with the requirements of a particular situation 65 as a consideration. Generally however the backing strip should be but slightly flexible, should preferably be solid with plane surfaces, and it is preferred that it be one of the various types of composition materials 70 available to the public. It may be of an asbestos composition when it is desired to effect a fire barrier, as for instance where the surface to which it is applied omits the coat of plaster, so that in effect the backing 75 will take the place of the fire resistant plaster. It may be a composition or other board of conventional construction if the surface to be treated is one which requires a seal to prevent the infiltration of dust, or insulation against the transmission of heat, or air, 80 as where the surface is mere studding, rafters, etc. The preferred material, however, is a fibrous, porous board which has of itself a relatively high co-efficient of sound absorption. Such a board or backing is 85 found in a certain material now before the public, which has a relatively high coefficient of sound absorption, about 31%, but which also has additional admirable characteristics for the purpose intended, inasmuch as it is substantially water-proof, thus preventing capillarity of the moisture from plaster of Paris when that is used in association with the backing strip, as later described, as well as affording a surface which forms a perfect bond with such plaster. 90

These attributes are, of course, of value in applying paste for the felt.

Assuming the desirability of a particular board to be known, desired lengths or sections thereof are provided, and to each section a layer of felt 12 is attached, which is of the same area as the section of the back-

ing and with the same angular outline, so that the side and end edges of the backing and of the felt are in registry substantially perpendicular to the plane of the surface of the backing. The felt is applied to the backing in any desired manner, as by paste, glue or cement.

To the exposed surface of the felt 12, a membrane 13 is attached, as by paste, glue or cement, in intimate association with the felt, as by the process known as "squee-gee", with an end and side of the membrane in registry with the perpendicular end 14 and side 15 of the unit, but with an end 16 and side 17 projecting beyond the registering edges of the felt and backing beneath them, and preferably the projecting portions of the flaps terminate in an uneven, ravelled or frayed edge 18. This unevenness is easily attained by the severance of the selvage of the membrane from the main body thereof, the edge of the flaps being thus uneven a blending effect is had with the surface upon which it is later overlapped. The membrane is preferably of a loosely woven material, such as gauze, cotton sheeting, burlap, etc., and which is the exposed element of the unit, which can later be painted or decorated as may be found most desirable.

Felt is so far as known, the most efficient sound absorbing medium available in the art, but it is difficult to handle due to its usually extreme pliability and lack of cohesion, and is of an uncompromising appearance. A membrane in contact with the felt, if of such porosity as to permit the passage of sound waves enhances the absorption of the felt by its own degree of absorption, or substantially so. This compensates somewhat for the necessity for a limit on the thickness of felt that can be used, as, although there is a higher absorption with the thicker felt, generally, yet, due to the inherent weakness of the felt such thickness as gives the utmost efficiency can tear itself apart of its own weight. Thus in practice, the ideal thickness of felt for the utmost of absorption cannot be availed of, and thinner felt must be used. This latter also because of the cost of the felt. As noted there is some compensation for this loss of efficiency by the use of the membrane, but the assembly is still short of perfection, that is, of total absorption. This is due in part to the transmission of sound through the assembled membrane and felt to the surface upon which they are mounted, and the reflection of such transmitted waves from the surface. If the surface is highly reflective the absorption is lower than if it is not reflective. Therefore, by forming the backing layer of sound absorbing material it has been possible to provide a unit of backing, felt, and mem-

brane, which all function in the absorption of sound, with a consequence of maximum absorption with such unit. This is to be understood as clearly differentiating from the assembly of a fibrous porous board and felt disclosed in the Patent #1,609,311, to Maurice C. Rosenblatt, as in that patent, the board being exposed did not transmit any sound waves to the inner layer of felt, the felt therein functioning as a vibration damper, and not as a sound absorber.

It is contemplated that the units so formed are to be applied to any desired surface, for which purpose a number of mechanical fastening devices may be used.

In one form of fastening the backing 11 is provided with a series of apertures 20 before the felt is applied, preferably, then the imposed membrane and felt are slit as at 21 in registry with the apertures. The slits are not slots nor openings but a division of the fibers so that the edges may be separated to admit a fastening device such as a screw or toggle bolt. In application in the latter case the unit is held against the surface in any desired manner, and holes are punched through the surface in registry with the apertures, using the slits and apertures as guides, and through which toggle bolts 22, having washers 23 may be passed to abut the felt side of the backing with the link 24 of the toggle in engagement with the inner side of the engaged surface.

In some cases it may be desirable to provide the rear faces of the backing with spring clips 25, such as will pass through metal lath and resiliently engage portions thereof, in order to maintain the units in their operative position.

Some surfaces have a tile or similar inner construction surfaced with a layer of plaster, to which units of this invention may be applied by the previous attachment of a key 26 to the rear face of the backing. The key may be a small section of metal lath, nails, screws, etc., as may be convenient. A section of the original plaster is chiseled out or otherwise removed, as at 27, in registry with the key of the unit to be applied thereover, which recess thus formed is filled with plaster of Paris into which the key of the unit is pressed. The setting of the plaster of Paris firmly anchors the unit by means of the keys. Such devices as the plaster of Paris plug may be used without any key if the unit includes as a backing the particular type of porous fibrous substantially water-proof composition material exemplified by certain materials now before the public, as the plaster secures a firm grip on the surface, and due to its nature there is no absorption of the water of the plaster, and firm anchoring of the backing and unit is had when the plaster of Paris sets. For this method of attachment it will be under-

stood that the plug of plaster of Paris projects slightly from the adjacent surface in which it is embedded, so as to be abutted by the re-inforcing layer of the acoustic unit. 5 (Not shown).

After their attachment in any desired manner or as disclosed, each unit is attached to the surface, with the adjacent unit in abutting engagement with the perpendicular 10 edge, the free edge of one unit abutting the flap carrying edge of another, being applied serially or successively to the surface. As first applied the flap projections hang freely from the units. The edges of the slits, if 15 any have been formed, are drawn together, and if necessary a little hair or felt is smeared with paste and rolled or worked into the slits to preserve the uniformity of the surface, as it is also inserted into what- 20 ever spaces or gaps there might be between adjacent units. Then the flaps of each unit are combed out, smeared with paste, etc., and squeegeed into substantially invisible association with the adjacent units, over the 25 joints between the units.

In using the invention it is the practice to pre-form a series of units at a desirable location, as in a factory or shop, and to transport a desired number to the work. Obviously they might be formed at the work but apart from it, to be subsequently attached as units. The operators necessary for the mere attachment of the units need not be highly skilled, and it will be clear that 35 if the area to be covered is not an exact multiple of the units, one or more units may be sawed or cut by the operators to fill in the odd areas. The acoustic surface thus created is one of high sound absorptive value, and 40 of attractive appearance, of itself, and further which can be decorated at will.

We claim as our invention:

1. The combination with a surface to be treated, of a plurality of acoustic units associated therewith in abutting relation, each unit comprising a backing board, a felt layer and a membrane, and means engaged be- 45

tween the surface and the backing board for positioning each unit.

2. The combination with a structural surface, of a sealing acoustic treatment connected thereto including a relatively stiff intermediate imposed layer of felt in intimate contacting association with said internal 55 layer, and an external exposed membrane in intimate contacting association with the layer of felt.

3. The combination with a surface to be treated, of an acoustic manipulatable unit, 60 said unit comprising a layer of reinforcing composition material arranged for association with mechanical fasteners, mechanical fasteners interposed between the layer and said surface, a layer of sound absorbing 65 material mounted on the re-inforcing material, and a woven membrane imposed upon the last mentioned layer and susceptible to decoration.

4. The combination with a structural element of a building, of an acoustic treatment connected therewith, comprising a layer of composition material having a relatively high co-efficient of sound absorption in juxtaposition to said element, an intermediate 75 layer of sound absorbing felt attached thereto in intimate connecting association therewith, and an external exposed layer of sound absorbing membrane attached to and in intimate contacting association with said felt. 80

5. The combination with a structural element of a building, of an acoustic treatment applied thereto and comprising an inner re-inforcing layer having mechanical fastening devices mounted thereon for engagement 85 with the element, and an outer acoustic assembly having a high co-efficient of sound absorption mounted on said inner re-inforcing layer.

In testimony whereof we affix our signatures.
